UNITED STATES PATENT OFFICE.

PHILIP T. BROWNELL, OF ELMIRA, NEW YORK.

IMPROVEMENT IN THREE-CYLINDER ENGINES.

Specification forming part of Letters Patent No. 147,599, dated February 17, 1874; application filed December 20, 1873.

To all whom it may concern:

Be it known that I, PHILIP T. BROWNELL, of Elmira, in the county of Chemung and State of New York, have invented a new and useful Improvement in Three-Cylinder Engines, of which the following is a specification:

Figure 1 is a detail section of a three-cylinder engine, taken through the line *x x*, Fig. 2, illustrating my improvements. Fig. 2 is a detail section of the same, taken through the line *y y*, Fig. 1. Fig. 3 is a side view of the bush before being cut into sections. Fig. 4 is an end view of the same after being cut into sections.

Similar letters of reference indicate corresponding parts.

My invention has for its object to furnish an improved bushing for the crank-pin of a three-cylinder engine, and an improved oiling device for the same, which shall be simple in construction and reliable in operation. The invention consists in a sectional bush for the wrist or crank pin of the engine, and in a lubricating device attached to said wrist-pin, and revolving with it, as hereinafter described.

A represents the steam-drum, and *B* the three cylinders, of the engine. *C* are the three pistons, and *D* are the piston-rods. Upon the inner ends of the piston-rods *D* are formed eyes, through which the crank-pin *E* passes, which eyes are made larger than the said crank-pin, to give space for the bushing. *F* is the bushing, which is turned up much heavier than for ordinary use, and the outside of which may be left smooth, or may be grooved to receive the eyes of the rods *D*. The turned plane or grooved cylinder is then cut longitudinally into four equal parts, which are arranged around the crank-pin *E*, within the eyes of the radial sliding rods *D*, and are secured to said eyes, one to each, in such positions as to give the proper bearing upon the pin. The inner surface of the eyes of the rods *D* are so formed as to permit a free movement over the parts of the bush that are fastened to the other eyes; or the bush-sections may be dressed down in the parts that the eyes move over. The shaft *H* has a disk, *G*, attached to its inner end, (a radial

arm would answer the same purpose,) and the wrist-pin *E* projects therefrom in a plane eccentric, but parallel to said shaft. Thus at each revolution the pin *E* describes a circle, whose center is the axis of the shaft. The oil for lubricating the bearings or bushings is held in and supplied from a cup, *I*, which is attached fixedly to the pin *E* by any suitable means, but is arranged eccentrically thereto, and concentrically with shaft *H*. Said cup is essentially in the form of a hollow truncated cone, and its base vertical, *i. e.*, parallel to the disk *G*. A supply-tube, *J*, passes through the side of the drum, and is curved at its inner end to deliver the oil into the cup. A small aperture is made through the base of the cup, beside the pin *E*, through which the oil passes to the bearings, &c. It will be seen that by this arrangement the cup *I* has two rotary movements—one on itself around the pin *E*, and another around a center which would be the axis of the shaft *H* if extended.

When the engine is at rest, the oil remains in the lower portion of the cup. When in motion, the oil is distributed in the cup, and carried around by centrifugal force, finding its way to the bearings.

A supplemental wrist-pin, having arm *K*, may be attached to the center of the cup *I*, *i. e.*, concentric with shaft *H* and disk *G*, for the purpose of operating the rotary valve of the engine.

Having thus described my invention, I claim as new and desire to secure by Letters Patent—

1. The sectional bush *F*, in combination with the eyes of two or more radial sliding rods, *D*, and with a pin, *E*, when two or more eyes work upon the same pin, substantially as herein shown and described.

2. The combination of the oil-cup *I* and oil-induction tube *J* with the pin *E*, bushing *F*, and rods *D*, and with the steam-drum *A* of a three-cylinder engine, substantially as herein shown and described.

PHILIP T. BROWNELL.
